UNITED STATES PATENT OFFICE

149,828

DESIGN FOR A STATUETTE

Charles Franklin Morse, Jr., Shaker Heights,
Ohio, assignor to Cleveland Base Ball Corporation, a corporation of Ohio

Application August 29, 1947, Serial No. 141,127

Term of patent 7 years

(Cl. D29—23)

To all whom it may concern:

Be it known that I, Charles Franklin Morse, Jr., a citizen of the United States, in the city of Shaker Heights, county of Cuyahoga, and State of Ohio, have invented a new, original, and ornamental Design for a Statuette, of which the following is a specification, reference being had to that accompanying drawing, forming a part thereof.

I claim:

The ornamental design for a statuette, substantially as shown.

CHARLES FRANKLIN MORSE, JR.
